UNITED STATES PATENT OFFICE.

AARON MOREHOUSE, OF ATLANTIC HIGHLANDS, NEW JERSEY, ASSIGNOR TO FRANK A. MOREHOUSE, OF ATLANTIC HIGHLANDS, NEW JERSEY.

BILL-FILE.

No. 870,244.

Specification of Letters Patent.

Patented Nov. 5, 1907.

Application filed May 17, 1907. Serial No. 374,149.

To all whom it may concern:

Be it known that AARON MOREHOUSE, a citizen of the United States, residing at Atlantic Highlands, in the county of Monmouth and State of New Jersey, has 5 invented certain new and useful Improvements in Bill-Files, of which the following is a specification.

This invention relates to paper files and binders and more particularly to the class known as bill files, and has for its object to provide a file so arranged that 10 papers may be easily engaged therewith or detached therefrom, but which will prevent the accidental disengagement of papers therefrom.

Another object is to provide a file which will include no sharp or exposed points with consequent danger to 15 papers or the person of the user.

A further object is to provide a structure which, while embodying the above enumerated advantages, will be simple and so arranged that it may be produced at a low figure.

20 Other objects and advantages will be apparent from the following description and it will be apparent that changes in the specific structure shown and described may be made within the scope of the claims, without departing from the spirit of the invention.

25 In the drawings forming a portion of this specification and in which like numerals of reference indicate similar parts in the several views. Figure 1 is a perspective view of the file, showing the method of engaging a piece of paper therewith. Fig. 2 is a front 30 elevation of the file.

Referring now to the drawings, the present invention includes a supporting board 5, to which the paper-receiving wire 6, is attached. This wire 6 includes two semi-circular end portions 7 and 8, overlapping 35 at their outer or free ends 7' and 8', these ends being beveled, as shown, to rest against each other. At their inner or connected ends, the end portions terminate in laterally extending loops 7^a and 8^a respectively, which project oppositely, and which receive 40 attaching screws 9 by which the wire is secured to the board.

In forming the paper-receiving wire, a length of ordinary wire of suitable stiffness is provided, which, adjacent to its center is curved outwardly, then rearwardly, and then inwardly to cross itself as at Y, thus 45 forming the loop 7^a. Beyond the point of crossing, the wire extends laterally and forwardly, as at X, and is then curved outwardly, then rearwardly, and then inwardly, to form the loop 8^a, beyond which a wire extends beneath the portion Y. The end portions of 50 the wire are then curved upwardly and toward each other in semi-circular shape, as previously described, the extremities thereof overlapping, as stated.

In engaging a piece of paper with the file, it is passed between the end portions 7' and 8', and is then brought 55 into engagement with the ends of one of these portions, which is thus caused to pass through the paper. It will be understood that by reason of the resilience of the wire, the two end portions 7 and 8 may be shifted to cause one of these end portions to lie at times at one 60 side of the other end portion and at times at the opposite side thereof.

The location of the loops at the opposite sides of the ring formed by the end portions 7 and 8, provides for the greatest resistance to the tendency of the file toward 65 lateral movement through separation of the overlapped end portions.

What is claimed is:

In a bill file, the combination with a support, of a single wire bent to form curved end portions having overlapping extremities and laterally extending oppositely disposed loops adjacent to the connected ends of the end portions, and fastening devices engaged in the loops and in the support, said overlapping end portions being located opposite to the loops and being movable away from each 75 other in a plane parallel to the plane of the loops for engagement of papers over the extremities of said end portions.

In testimony whereof he affixes his signature, in presence of two witnesses.

AARON MOREHOUSE.
